[57] CLAIM

The ornamental design for extension handle for a recliner, as shown and described.

DESCRIPTION

FIG. 1 is a front, top and left side perspective view of an extension handle for a recliner showing my new design; FIG. 2 is a bottom plan view thereof; the top plan being a mirror image;

FIG. 3 is a right side elevational view thereof; and,

FIG. 4 is a front elevational view thereof, the rear elevational view being a mirror image;

FIG. 2-4 are on an enlarged scale.

Broken line showing of the handle attaching to the recliner is for illustrative purposes only and forms no part of the claimed design.
